SUBMERSIBLE STRUCTURE

Earl Mendenhall and Junius B. Van Horn, Los Angeles, Calif., assignors to Menhorn, Inc., Los Angeles, Calif., a corporation of California

Application September 26, 1932, Serial No. 634,911

11 Claims. (Cl. 103—102)

Our invention relates to a submersible structure which encloses a bearing or other element which might be detrimentally affected by contact with the liquid in which the structure is submerged. More particularly, the invention is directed to a submersible structure in which the internal pressure can be changed relative to the pressure of the surrounding liquid by means of a pumping structure or by other pressure-changing means, and is not limited to the particular element enclosed by the structure.

The present application is a continuation-in-part of our copending application entitled "Bearing structure", Serial 220,382, filed September 19, 1927. That application discloses two forms of submersible structures, one in which the internal pressure is maintained substantially equal to the pressure at the depth of submergence and being of utility without regard to its use with a system for changing the internal pressure, and the other in which the internal pressure is changed relative to the pressure at this depth of submergence. It is to the latter type of structure that the present application is particularly directed, our application Serial No. 634,908 being directed to the former type of structure and containing claims on the combination irrespective of the general use of a pumping means or other means for changing the internal pressure.

It is often desirable to be able to maintain the pressure inside the submerged structure at a value somewhat higher than the pressure of the surrounding liquid. This is especially true in certain installations wherein segmental or sectional enclosing structures are utilized. Any differential pressure on such a segmental enclosing structure will tend to force liquid into or from the structure depending upon whether the pressure is greater outside or inside thereof. It is sometimes difficult to maintain a fluid-tight joint on such a segmental shell, especially after the structure has been submerged for a long period of time. So also, it is sometimes difficult to obtain castings which are entirely impervious. Any minute pin holes in such a casting might permit the external liquid to enter the submerged structure with possible detrimental results.

It is an important object of the present invention to provide a submersible structure in which the pressure inside thereof can be changed relative to the pressure at the depth of submergence, this pressure being usually main-

tained somewhat above the pressure of the external liquid at the depth of submergence.

The present structure is directed to a submersible unit from which a rotatable shaft extends. To prevent the external liquid from entering the interior of the structure it is necessary to provide a suitable seal. In the preferred embodiment of the present invention we have found it desirable to substantially equalize the pressures on opposite sides of this seal, thereby eliminating any pressure differential on the seal tending to force liquid therethrough and thus permitting the use of a fluid-packed seal.

It is an object of the present invention to provide a sealed submersible structure in which the pressures on opposite sides of the seal are substantially equalized at a pressure different from the pressure at the depth of submergence of the structure.

It is an object of the present invention to provide a structure in which the internal pressure can be built up to a value in excess of the pressure at the depth of submergence and in which this increased internal pressure is transmitted to opposite sides of a seal acting to seal a shaft with respect to the structure.

Further objects of the invention lie in the particular pressure-transfer system utilized.

The excess internal pressure can be developed by any one of several means, such, for instance, by the use of a suitable pumping means. The utilization of such systems forms a part of the present invention.

If the pumping means is utilized, this means may conveniently be connected to the shaft extending from the structure. It is an object of the present invention to provide a pumping chamber communicating with the seal and with the pressure-transfer means, the pressure in this pumping chamber being controlled by a pump driven by the shaft.

Such a pump may be of relatively small capacity, being utilized only for the purpose of maintaining the internal pressure. In other instances it is convenient to utilize a larger pump means developing a sufficient head to force a considerable volume of liquid to a point above the surface of the external liquid in which the structure is submerged. Both systems are comprehended in the present invention.

A further object of the invention is to provide a structure in which any of the external liquid which enters the structure under the action of the pumping means passes through a

restricted passage which strains therefrom any abrasive particles or other foreign matter.

Another object of the invention is to provide an improved structure which is very effectively sealed, thereby permitting the use therein of a moisture-sensitive structure.

Other objects and advantages of the invention will be made evident hereinafter.

In the drawing,

10 The figure is a view of one form of the invention shown in conjunction with a turbine pump.

In the figure, we have shown the invention as applied to one form of deep-well turbine pump unit indicated in general by the numeral 10. 15 Such a pump unit may be submerged in the external liquid which is to be pumped and may be lowered into a well below the level of the liquid therein. In other instances the unit may be lowered beneath the surface of a lake or other 20 body of liquid.

Such a pump unit may conveniently comprise upper and lower bearing or enclosing structures 11 and 12 separated by one or more pump bowls 13, the whole structure being suitably connected together by suitable means and being suspended 25 on a discharge pipe 17 which conducts the pumped liquid upward to a point above the surface of the external liquid. A shaft 18 extends downward through the discharge pipe 17 and 30 drives the unit.

The upper enclosing structure 11 is shown as including a casing 21 and a shell 22 spaced from each other to define an annular discharge passage 23, webs 24 extending across this discharge 35 passage to support the shell inside the casing. The unit is suspended from the lower end of the discharge pipe 17, this pipe being shown as threaded into the upper end of the casing 21. The upper end of the shell 22 is closed by an 40 upper end wall 26 which provides an opening 27 which is slightly larger in diameter than the shaft 18 to define a passage 28. This opening is enlarged to define an upper annular or auxiliary chamber 29 which surrounds the shaft.

45 Separating this annular chamber 29 from the interior of the shell 22 is a seal 30. Various types of well-known seals may be utilized, but for most exacting requirements we have found it necessary to utilize a fluid-packed seal. The details of the seal herein shown are not per se a part of the present invention, the details thereof being claimed in our copending application Serial No. 225,182, entitled "Emulsion preventing seal", now Patent No. 1,879,626, granted September 27, 1932. Essentially, the type of seal shown comprises a cup 32 secured in fluid-tight relationship with the shaft 18 so as to rotate therewith. This cup thus provides an annular chamber around the shaft which chamber contains a body of sealing liquid such as mercury. Extending downward to a point below the surface of this sealing liquid is a stationary apron 33 which is secured in fluid-tight relationship to the upper end wall 26. It is usually desirable to maintain a body of internal liquid inside 55 the shell 22, and it will thus be clear that this internal liquid communicates with one portion of the seal 30, while the liquid in the annular chamber 29 communicates with another portion of this seal. These portions will be respectively referred to hereinafter as internal and external portions, and with the type of seal shown, the surface of the sealing liquid between the cup 32 and the apron 33 may comprise the internal portion, while the surface of the seal-

ing liquid between the shaft 18 and the apron 33 may comprise the external portion. In other types of seals these portions will be somewhat different.

5 In the preferred embodiment of the invention the interior of the shell 22 is divided by a baffle 38 into a main or bearing chamber 39 and a pressure-transfer chamber 40 forming a part of the pressure-transfer system to be herein-after described. A bearing 42 of suitable type 10 is positioned in the chamber 39 to journal the shaft 18, this bearing being lubricated by the surrounding internal liquid.

15 The shaft 18 extends completely through the main chamber 39 and extends from the enclosing structure 11 through a lower end wall 43 of the shell 22. This end wall provides an opening 44 slightly larger than the shaft 18 to define an annular passage 45 which communicates with a lower annular or auxiliary chamber 20 46 formed at an intermediate section of the opening 44. The annular chamber 46 is in open communication with the upper annular chamber 29 through a passage 47 formed in the walls 25 of the shell 22.

It is desirable to utilize a second seal 50 to seal the shaft with respect to the lower end of the enclosing structure 11. We have shown this seal as being of the same type as the seal 30, including a cup 51 secured to the shaft and 30 an apron 52 secured in fluid-tight relationship with the baffle 38. It is preferable to position the seal 50 in a seal chamber 53 spaced from the pressure-transfer chamber 40. These chambers may be spaced vertically with respect to 35 each other, but in view of space considerations we have shown the balance chamber as surrounding the seal chamber. This may be accomplished by the use of a downward extending portion 54 of the baffle 38. One or more openings 55 permit communication between the seal chamber 53 and the lower end of the pressure-transfer chamber 40. Similarly one or more small openings 56 permit communication between the main chamber 39 and the upper end 45 of the pressure-transfer chamber 40.

The lower end of the enclosing structure 11 defines an impeller or pumping chamber 60 in which an impeller 61 is positioned, this impeller being secured to the shaft 18 in a well-known 50 manner. One or more of the pump bowls 13 are secured to the lower end of the enclosing structure 11 and provide passages 63 through which the external liquid is drawn by the rotation of the impeller 61, this external liquid then 55 being forced upward through the passages 23 and to the surface of the ground through the discharge pipe 17. In the form shown, two pump stages are shown, the lower stage including a pumping chamber 64 in the bowl 13 and 60 in which an impeller 65 is positioned.

Secured below the bowl 13 is a lower enclosing structure 12 into which the lower end of the shaft 18 extends. This lower enclosing structure is somewhat similar to the enclosing 65 structure 11, providing a casing 71 and a shell 72 mounted therein, these elements being spaced from each other to define a passage 73 communicating with the intake of the impeller 65 and with the external liquid. The upper end of the shell 72 is in the form of an upper end wall 75 providing an opening 76 slightly larger in diameter than the shaft 18 so as to define an annular passage 77 therearound. This passage is enlarged at an intermediate section to define 75

an upper annular or auxiliary chamber 78. A seal 80 of the type previously described may be used to seal the shaft with respect to the upper end wall 75, the external portion of this seal communicating with the annular chamber 78 through the lower end of the annular passage 71, and the internal portion thereof communicating with a bearing chamber 81 defined in the shell 72 above a baffle 83. A bearing 84 is positioned in the bearing chamber 81 and is surrounded by the internal liquid maintained in this chamber. It will be noted that in this structure the baffle 83 extends across the lower end of the shaft 18, thus defining a pressure-transfer chamber 86 therebelow. The lower end of the pressure-transfer chamber 86 communicates with the upper annular chamber 78 through a passage 88. The lower end of the lower enclosing structure 12 is closed off by a lower end wall 89.

When the pump unit 10 is submerged, and the shaft 18 is not rotating, it will be clear that the pressure in the main chambers 39 and 81 will be substantially equal to the pressure at the depth of submergence of these chambers. This will be readily apparent when it is considered that the external liquid will be at a level in the pipe 17 corresponding to the level of the liquid in which the pump unit is submerged. The lower end of the pressure-transfer chamber 40 thus has access to the external liquid through the annular passage 45 and the openings 55 in the portion 54 of the baffle 38. This external liquid is ordinarily water and of greater density than the internal liquid filling the main chamber 39 so that bodies of these liquids will be maintained in the pressure-transfer chamber 40, these bodies of liquid being in surface contact with each other, this surface of contact being indicated by the numeral 94. The openings 56 in the baffle 38 interconnect the upper end of the pressure-transfer chamber 40 and the main chamber 39 so as to insure that the pressure in this main chamber will be equal to the pressure in the pressure-transfer chamber 40. It will thus be apparent that the pressures on opposite portions of each of the seals 30 and 50 are maintained substantially equal, for the internal portion of each seal is in open communication with the internal liquid, while the external portion of each seal is in open communication with the external liquid present in the seal chamber 53 and in the annular chamber 29. The passage 47 communicating between the upper and lower annular chambers 29 and 46 insures that the pressures in these chambers will be maintained equal, disregarding the pressure head due to the difference in elevation of these chambers. Any change in the head of the external liquid will, of course, be transmitted through the annular passages 28 and 45 to the seals 30 and 50 and to the pressure-transfer chamber 40.

Similarly, the pressure-transfer chamber 86 of the lower enclosing structure 12 will maintain the pressure in the main chamber 81 substantially equal to the pressure of the external liquid at the depth of submergence. In this instance, the external liquid communicates with the upper annular chamber 78 and with the outer portion of the seal 80 through the annular passage 71, the passage 88 transferring this pressure of the external liquid in the annular chamber 78 to the lower portion of the pressure-

transfer chamber 86. Contacting bodies of the internal and external liquids may thus be maintained in the chamber 86, the surface of contact being indicated by the numeral 95. The openings 87 in the baffle 83 insure that the internal liquid in the main chamber 81 will be maintained at substantially this same pressure whereby the pressures on opposite portions of the seal 80 are substantially equalized.

When the shaft 18 is rotated, as by a suitable drive means positioned above the surface of the external liquid, the rotation of the impellers 61 and 65 increases the pressure in the passages 23 and 63, thus forcing the external liquid upward in the discharge pipe 17. As the pressure in the pumping chamber 60 increases, this increased pressure is transmitted to the pressure-transfer chamber 40 through the annular passage 45, this chamber acting to correspondingly build up the pressure on the internal liquid in the main chamber 39. It will be clear, however, that the position of the surface of contact 94 will not perceptibly change due to the incompressibility of the internal liquid in the main chamber 39.

So also, the increased pressure in the discharge pipe 17 will be transmitted to the upper annular chamber 29 through the annular passage 28. This pressure will in turn be transmitted through the passage 47 to the lower annular chamber 46.

To prevent any abrasive material carried by the pumped liquid from entering the annular passage 28 it is usually desirable to provide a suitable straining means. In the form shown in the figure this means includes an inverted cup 96 secured to the shaft and which extends downward over a neck 97 of the upper end wall 26. The inverted cup is, however, spaced a minute distance from the periphery of the neck 97 so as to provide an annular passage through which the external liquid must flow upward before it can enter the annular passage 28. This restricted passage and the upward flow thus strains any abrasive particles from the external liquid.

Similarly, the change in pressure in the pumping chamber 64 is transmitted to the interior of the main chamber 81 through the pressure-transfer chamber, as previously described. We have shown the lower impeller 65 as including an eye 98 extending downward around a neck 29 of the upper end wall 75 to define a restricted throttle or straining passage similar to the one previously described for the upper enclosing structure 11 and transmitting the pressure-changes set up near the eye 98 of this impeller.

In installing the pump unit the main chambers 39 and 81 may be filled with a neutral liquid before the unit is submerged. No difficulty will be encountered with the lower enclosing structure 12, for the correct amounts of internal and external liquids may be inserted without danger of these liquids leaking therefrom. The passage 88 retains a column of liquid which maintains the bodies of liquids in equilibrium during installation. In installing the upper enclosing structure 11 a greater degree of care must be exercised. The internal liquid may be inserted as this bearing structure is being submerged, the internal liquid being introduced through an opening 100 in sufficient quantities to maintain the surface of contact 94 within the pressure-transfer chamber 40 and approximately in the

position shown. A plug 101 may subsequently be screwed into the opening 100 to close off all communication therethrough. Once the upper bearing structure 11 is submerged, the pressure-transfer system will operate as previously described, and the internal liquid will be retained in the upper end of the main chamber 39. If the unit is lowered into an inaccessible position, it may be desirable to utilize a suitable packing 10 to seal off the lower end of the annular passage 45 during the lowering of the unit. Such a structure will permit filling of the chambers 39, 40, and 53 with the proper amounts of internal and external liquids before the unit is submerged.

While we have shown the pressure-transfer means as comprising contacting bodies of the internal and external liquids, it should be understood that we are not limited to such a construction. If desired, other pressure-transfer means may be utilized, such as a diaphragm, collapsible bellows, or other member separating two liquids.

In conclusion, one of the important features 25 of the invention is to utilize a pressure inside a submerged shell which is different from the pressure at the depth of submergence regardless of whether this pressure is developed by a pumping means or by other means. If the internal 30 pressure is maintained greater than the external pressure any tendency toward leakage will be outward rather than inward so that none of the external liquid will enter the shell.

Another important feature of the invention 35 which is particularly desirable in certain installations is the maintenance of a differential pressure inside and outside the submerged unit, together with the maintenance of substantially equal pressures on the seal.

40 We claim as our invention:

1. In a submersible structure adapted to be submerged in an external liquid, the combination of: an enclosing structure; walls extending across the interior of said enclosing structure 45 and dividing this interior into an upper chamber, an intermediate chamber, and a lower pressure-transfer chamber, said intermediate and said lower chambers communicating with each other; a shaft extending from said intermediate chamber through said upper chamber; a sealing means around said shaft and sealing said upper chamber from said intermediate chamber, said sealing means providing external and internal portions respectively communicating with said upper and intermediate chambers; means changing the pressure in said upper chamber with respect to the pressure of said external liquid in which said structure is submerged; walls forming a passage communicating with 50 said upper chamber and extending downward below said intermediate chamber to communicate with said lower chamber to substantially equalize the pressures on said external and internal portions of said sealing means.

60 2. In a submersible structure, the combination of: walls defining a main chamber containing an internal liquid; a rotatable shaft extending upward from said chamber; walls defining an annular chamber above said first-mentioned chamber; pump means operated by said shaft for changing the pressure in said annular chamber when said shaft is rotated; a sealing means around said shaft and separating said chambers, said sealing means providing an internal portion 65 communicating with said main chamber and an

external portion communicating with said annular chamber; and walls defining a passage communicating between said chambers to substantially equalize the pressures therein and thus substantially equalize the pressures on said internal and external portions of said sealing means.

5 3. In a submersible structure adapted to be submerged in an external liquid, the combination of: walls forming an upper chamber communicating with said external liquid; walls defining a main chamber below said upper chamber and substantially filled with an internal liquid; a rotatable shaft extending from said main chamber into said upper chamber; a sealing means 10 around said shaft and separating the liquids in said upper and main chambers; a pump means operated by said shaft and increasing the pressure in said upper chamber when said shaft is rotated; walls defining a pressure-transfer chamber communicating with said main chamber and containing pressure-transferring bodies of said internal and external liquids; and walls forming a passage communicating with said upper chamber and with said pressure-transfer 15 chamber to conduct external liquid from said upper chamber to said body of external liquid in said pressure-transfer chamber.

20 4. In a submersible structure adapted to be submerged in an external liquid, the combination of: a shell including a main chamber containing an internal liquid; pressure-transfer means controlling the pressure on said internal liquid; a rotatable shaft extending upward from said main chamber; a sealing means sealing the junction of said shaft and said shell; walls defining a pumping chamber above said main chamber; pump means driven by said shaft and changing the pressure in said pumping chamber when said shaft is rotating; walls 25 defining an auxiliary chamber around said shaft and positioned between said pumping chamber and said main chamber to communicate with said sealing means and said pressure-transfer means; walls defining a space communicating between said pumping chamber and said auxiliary chamber to transmit to said auxiliary chamber and to said pressure-transfer means the pressure variations developed by the operation of said pump; and walls defining a passage 30 communicating between said auxiliary chamber and said pressure-transfer means.

25 5. In a submersible structure adapted to be submerged in an external liquid, the combination of: walls defining a chamber; a bearing in 55 said chamber; a shaft journaled in said chamber and extending upward through said walls; sealing means at the junction of said shaft and said walls above said chamber and providing internal and external portions, said internal 60 portion communicating with said chamber; walls defining a pumping chamber; a pumping means in said pumping chamber and driven by said shaft to change the pressure therein; walls defining a passage communicating between said pumping chamber and said external portion of said sealing means whereby changes in pressure in said pumping chamber are transmitted to said external portion of said sealing means; and an auxiliary passage communicating with 65 said first-named passage for transmitting the pressure of said first-named passage to the interior of said chamber whereby the pressure on said internal portion of said sealing means is maintained substantially equal to the pressure 70 75.

on said external portion of said sealing means, these pressures changing with change in pressure in said pumping chamber.

6. In a submersible structure adapted to be submerged in an external liquid, the combination of: a shell; a baffle means extending across said shell to divide the interior thereof into a main chamber thereabove and a balance chamber therebelow, said baffle means defining a port through which said chambers are in communication, said main chamber being substantially filled with an internal liquid, and said balance chamber containing contacting bodies of said liquids; a shaft extending upward from said main chamber, the lower end of said shaft terminating above said baffle means; walls forming an auxiliary chamber around said shaft above said main chamber; a sealing means separating said main and auxiliary chambers, one portion of said sealing means communicating with said auxiliary chamber and another portion thereof communicating with said main chamber; walls defining a passage communicating between said body of external liquid in said balance chamber and said auxiliary chamber; walls defining a pumping chamber into which said shaft extends; walls defining a passage communicating with said pumping chamber and with said first-named passage and said auxiliary chamber whereby a change of pressure in said pumping chamber is transmitted to said auxiliary chamber and to said pressure-balance chamber to maintain the pressures on said portions of said sealing means substantially equal; a pump means in said pumping chamber and driven by said shaft to change the pressure in said pumping chamber; and walls defining a passage communicating between said external liquid and said pumping chamber.
7. In a submersible structure adapted to be submerged in an external liquid, the combination of: submerged walls forming a main chamber containing an internal liquid; a shaft extending from said main chamber; walls defining an annular chamber above said main chamber and around said shaft; a sealing means separating said main chamber from said annular chamber; walls defining a restricted passage communicating between said external liquid and said annular chamber and through which said external liquid may reach said annular chamber; and means for substantially equalizing the pressures on opposite sides of said seal at a pressure higher than the pressure of said external liquid at the depth of submergence of said submerged walls, said means including means building up the pressure in one of said chambers to said higher pressure and including pressure-transfer means transferring said higher pressure to the other of said chambers.
8. A combination as defined in claim 7 in which said restricted passage is formed at the junction of said shaft and said walls defining said annular chamber.

9. In a submersible structure adapted to be submerged in an external liquid, the combination of: walls defining a main chamber containing an internal liquid; walls defining an auxiliary chamber at one end of said main chamber; a pressure-transfer means including walls defining a balance chamber containing bodies of said internal and external liquids in pressure-transferring relationship, said balance chamber being positioned at the other end of said main chamber; a shaft extending from said main chamber into said auxiliary chamber; a seal associated with said shaft for sealing said main chamber and said auxiliary chamber; means building up in said auxiliary chamber a pressure greater than the pressure at the depth of submergence of said structure whereby this increased pressure is transmitted to that one portion of said seal communicating with said auxiliary chamber; and walls defining a passage connecting said auxiliary chamber at one end of said main chamber and said balance chamber of said pressure-transfer means at the other end of said main chamber to transmit pressure variations in said auxiliary chamber, which variations affect said one portion of said seal, to said main chamber and thus to that portion of said seal communicating with said main chamber.

10. A combination as defined in claim 9 in which said passage is formed exterior of said main chamber.

11. In a submersible structure adapted to be submerged in an external liquid, the combination of: walls defining a main chamber containing an internal liquid; walls defining an auxiliary chamber communicating with said external liquid; a shaft extending from said main chamber into said auxiliary chamber; a seal associated with said shaft and separating said internal liquid in said main chamber from the external liquid in said auxiliary chamber; pressure-transfer means communicating with said main and auxiliary chambers whereby pressure variations in one of said chambers are transmitted to the other of said chambers to substantially equalize the pressures on opposite sides of said seal, said pressure-transfer means including walls defining a balance chamber containing bodies of said internal and external liquids in pressure-transferring relationship and respectively communicating with said main and auxiliary chambers; a pumping means operatively associated with said shaft and spaced from said auxiliary chamber; and means for transmitting the pressure variations set up by said pumping means to one of said chambers, said pressure-transfer means thus transferring these pressure variations to the other of said chambers.
